UNITED STATES PATENT OFFICE.

EDWARD A. BAKER AND SAMUEL W. JOHNSTON, OF MANSFIELD, OHIO.

PUMP.

1,178,206.

Specification of Letters Patent.

Patented Apr. 4, 1916.

Application filed May 15, 1915. Serial No. 28,488.

To all whom it may concern:

Be it known that we, EDWARD A. BAKER and SAMUEL W. JOHNSTON, citizens of the United States of America, residing at Mansfield, in the county of Richland and State of Ohio, have invented certain new and useful Improvements in Pumps, of which the following is a specification.

This invention relates to certain new and useful improvements in pumps and more particularly to that type of pumps in which is employed a rotary element for raising liquids, and it has for its primary aim to provide a novel, simple and cheaply constructed machine which will efficiently raise water in a steady and continuous flow.

Further objects reside in the provision of a pump in which a liquid elevating screw is substituted for the usual piston and cylinder and in which the parts are mounted to be subject to a minimum wear.

These, among other objects herein set forth, are attained by the construction illustrated in the accompanying drawings, minutely described in the following specification, and succinctly defined in the annexed claims.

In the drawings: Figure 1 is a broken view of a pump embodying the preferred form of the invention, parts being in section; Fig. 2 is an enlarged sectional view of the upper portion of the pump casing with the driven gear mounted thereon; Fig. 3 is a horizontal section on line 3—3 of Fig. 1; Fig. 4 discloses the pump cylinder in section with the liquid elevating screw arranged therein; Fig. 5 is a horizontal section thereof on line 5—5 Fig. 4; and Fig. 6 is a bottom plan of the pump cylinder.

Referring more particularly to the drawings, in which like characters of reference denote corresponding parts throughout the several views, the numeral 1 designates the pump casing, of hollow and, preferably, cylindrical formation, supported by a suitable base 2 and provided with a spout 3. To the upper end of the casing 1 is screw threaded a cap 4 having a central bore and a counter bore or concentric recess 5 adapted

to receive the depending annular boss 6 of 50 a collar bearing 7 which latter is also formed with a bore coincident with the bore of cap 4 and supports a bevel gear 8. Suitable anti-friction bearings 7' are interposed between the collar and cap. The gear 55 9 is fixed to the upper end of a tubular rod 9 by a screw 10, or other fastening means, said screw doubly securing the gear against relative rotary movement on the pump rod 9 by entering an aperture provided in the 60 latter. A bracket 11, detachably secured to the upper end portion of the pump casing, is provided with a bearing 12 for the shaft 13 of a drive bevel gear 14 which meshes with gear 8 and may be rotated by 65 power although the present showing adapts the pump for manual operation, a crank handle 15 being fixed on the opposite end of the gear supporting shaft 13. Threaded on the lower end of the pump casing is 70 a head 16 of the pump cylinder 17, the latter being threaded into head 16 and head 18 whereby the interior is accessible. The upper cylinder head 16 is formed with an opening coincident with the chamber of 75 the casing and across which a spider 19 is arranged to provide a bearing for the pump rod or shaft 9. The lower head 18 is of open or spider formation having a central opening 20 and a surrounding, internally 80 threaded boss 21 in which a collar bearing 22 is threaded, the latter being formed with a ball race or groove on its upper face to receive the ball bearings 23. The open space of the lower head is covered by a screen 26' 85 which is clamped between the adjacent end of the cylinder and the head for straining out impurities in the water. The lower end of shaft 9 engages in a counter bore 25 of the collar bearing 22 and has fixed thereto above the latter a collar 26 which rests on the ball bearings to support the shaft. Fixed on the shaft between the collar 26 and spider 19 is a spiral blade or screw impeller 27 having preferably a pitch 90 of 30°, the peripheral edge of the blade lying in proximity to the cylinder wall.

The operation is obvious from the fore-

going, it being noted that the water or other liquid is continuously elevated on rotating the blade with its shaft 9, such movement being imparted to the latter from handle 15 by bevel gears 10 and 14. The ratio of the gears may be varied, as circumstances require.

It is further noted that there is little wear of the parts since the shaft and blade are supported vertically in the cylinder and casing.

By having the shaft hollow, the air is displaced within the former as the water is elevated which acts more or less as a balance or pressure equalizer, the bore of the shaft registering with the opening 20 for communicating below the cylinder.

What is claimed is:

1. In combination with a pump cylinder, 20 and a shaft having a spiral blade thereon, said cylinder having an exteriorly threaded lower end, a head threaded over said cylinder lower end and having a spider abutting the bottom end of the cylinder, an internally threaded boss connected to the spider and extending above the spider and having its bottom extending flush with the bottom of said head, a collar bearing threaded into said boss and having a bore in which the 30 lower end of said shaft rotates, balls on the collar, and a collar on the shaft seating on said balls, said boss and collar bearing having central registering openings and said shaft having its lower end terminating between the ends of the first collar, and being 35 hollow and registering with the openings in the boss and collar.

2. In combination with a pump casing, a head secured to the lower end thereof, a 40 pump cylinder connected to the head, a head connected to the lower end of the cylinder and formed with a spider having a central bearing, a central bearing borne by the first head, a hollow rod extending into the casing and journaled in said bearings, and a spiral blade carried by the rod to fit the cylinder, said blade extending from a point closely adjacent the upper bearing to a point closely adjacent the lower bearing, the reduced casing being secured to the upper bearing to receive water from the cylinder, and said spider providing a substantially annular inlet into the lower end of the cylinder, said blade being continuous 55 whereby the water that passes through the cylinder is constantly acted upon and uninterruptedly raised in its passage throughout the length of the cylinder, the central bearing for the lower end of the rod being 60 so arranged as to permit free and unobstructed inflow of water into the inner periphery of the hollow rod.

3. In combination with a pump casing, a head secured to the lower end thereof, a

pump cylinder connected to the head, a head 65 connected to the lower end of the cylinder and formed with a spider having a central bearing, a central bearing borne by the first head, a hollow rod extending into the casing and journaled in said bearing, a spiral 70 blade fitted to the inner periphery of the cylinder and carried by the hollow rod; said blade extending from a point adjacent to the upper bearing to a point closely adjacent the lower bearing, a collar formed on 75 the upper head, said casing being smaller in diameter than the cylinder, and attached to the collar of the upper head thereby suspending and supporting the cylinder; said spider providing a substantially annular inlet into the lower end of the cylinder and said blade being continuous whereby the water that passes through the cylinder is constantly acted upon and uninterruptedly raised in its passage throughout the length 80 of the cylinder in juxtaposition with the upper head and forced through apertures in the head which are restricted to the size or smaller than the inner periphery of the small casing.

4. In combination with a pump casing, a head secured to the lower end thereof, a pump cylinder connected to the head, a head connected to the lower end of the cylinder and formed with a spider having a central bearing, a central bearing borne by the first head, a hollow rod extending into the casing and journaled in said bearing to continually maintain the inner periphery thereof free from obstruction and open to admit 100 the inflow of water to assist in supporting the pump mechanism, a spiral blade fitted to the inner periphery of the cylinder and carried by the hollow rod; said blade extending from a point adjacent to the upper 105 bearing to a point closely adjacent the lower bearing, a collar formed on the upper head, said casing being smaller in diameter than the cylinder, and attached to the collar of the upper head thereby suspending and supporting the cylinder; said spider providing a substantially annular inlet into the lower 110 end of the cylinder and said blade being continuous whereby the water that passes through the cylinder is constantly acted upon and uninterruptedly raised in its passage throughout the length of the cylinder in juxtaposition with the upper head and forced through apertures in the head which are restricted to the size or smaller than the 115 inner periphery of the small casing.

5. In a pump, an elongated vertical cylinder, a combined head and spider secured to the lower end thereof, a central bearing carried by the spider, a head for the upper 125 end of the cylinder provided with an upstanding collar of reduced size, a casing secured to the collar, a hollow shaft mounted

upon the bearing carried by the spider, the upper portion thereof fitting an aperture formed in the upper head, a spiral blade carried by the hollow shaft and extending 5 from a point slightly above the lower head to the bottom of the upper head; said hollow shaft being mounted upon the lower

central bearing to always maintain the end free from obstruction and open to the inflow of water for the purpose described. 10

In testimony whereof we affix our signatures.

EDWARD A. BAKER.

SAMUEL W. JOHNSTON.
